UNITED STATES PATENT OFFICE.

ORTON G. CAMPBELL, OF ANTELOPE GAP, TEXAS.

DESIGN FOR A CURLING-IRON HOLDER.

SPECIFICATION forming part of Design No. 27,168, dated June 8, 1897.

Application filed April 2, 1897. Serial No. 630,487. Term of patent 7 years.

To all whom it may concern:

Be it known that I, ORTON G. CAMPBELL, a citizen of the United States, residing at Antelope Gap, in the county of Mills and State of Texas, have invented and produced a certain new and original Design for Curling-Iron Holders; and I do declare the following to be a full, clear, and exact description of the invention, such as will enable others skilled in the art to which it appertains to make and use the same.

My invention relates to a new and original design for a curling-iron holder, by means of which the curling-iron may be supported within a lamp-chimney and be heated; and the invention consists of a holder of the configuration and ornamentation shown in the accompanying drawing, in which the holder is represented in perspective.

The leading feature of my design consists of a straight vertical body 1, formed of twisted strands 2 and having at its lower end a hori-

zontally-extended loop 3 and at its upper end a coincident horizontally-extending loop 4, formed of the twisted strands 2 and 2 and the laterally-extended arms 5, projecting on opposite sides of the body and formed of the twisted strands 2, and terminating in downwardly-extending loops 6, which are bent upwardly, as shown at 7. A vertically-extending loop 8 projects upwardly from the upper side of this cross-bar and is formed from the twisted strands 2 and terminates in a downwardly-curved twisted extension 9.

What I claim is—

The design for a curling-iron holder, as herein shown and described.

In testimony whereof I hereunto affix my signature in presence of two witnesses.

ORTON G. CAMPBELL.

Witnesses:

THOMAS BURROWS,
THOMAS CALDWELL.
